US00D882668S

(12) **United States Design Patent** (10) Patent No.: **US D882,668 S**
(45) Date of Patent: **** Apr. 28, 2020**

(54) **LENS FOR CAMERA**

(71) Applicant: **FUJIFILM Corporation**, Tokyo (JP)

(72) Inventor: **Haruka Ikegame**, Saitama (JP)

(73) Assignee: **FUJIFILM Corporation**, Tokyo (JP)

(**) Term: **15 Years**

(21) Appl. No.: **29/654,761**

(22) Filed: **Jun. 27, 2018**

(30) **Foreign Application Priority Data**

Dec. 28, 2017 (JP) 2017-029491
